UNITED STATES PATENT OFFICE.

CHARLES GREY HILL, OF DAYBROOK, ENGLAND.

STOP-MOTION FOR CIRCULAR LOOMS.

No. 814,290.

Specification of Letters Patent.

Patented March 6, 1906.

Application filed October 3, 1904. Serial No. 227,042.

To all whom it may concern:

Be it known that I, CHARLES GREY HILL, a subject of the King of Great Britain, and a resident of Daybrook, in the county of Nottingham, England, have invented certain new and useful Improvements in Stop-Motions for Circular Looms, of which the following is a specification.

This invention relates to improvements in circular looms, such as described in the specification of Letters Patent No. 689,490, dated December 24, 1901, and refers more particularly to automatic stop mechanism for such looms.

Owing to the fact that positively-driven shuttles are employed with a very limited space between them, it is found necessary to provide mechanism that will at once stop the loom should any one shuttle meet with an obstruction in the shed. Such obstruction is generally caused by a broken warp-thread, which is, owing to the construction of the loom, drawn into the shed by one shuttle and prevents the shed from subsequently opening for the next following shuttle. An obstruction in the shed, however caused, does serious damage and entails considerable loss of time if the loom is not immediately stopped; and the object of the present invention is to provide automatic mechanism that will immediately stop the loom when an obstruction occurs.

Referring to the drawings, Figure 1 is a sectional elevation showing part of a loom to which my invention is applied. Fig. 2 is a sectional elevation, and Fig. 3 a plan, showing a shuttle and the supporting and propelling mechanism for the same. Fig. 4 is a side elevation, Fig. 5 a plan, and Fig. 6 a vertical cross-section, of a shuttle. Fig. 7 is a sectional elevation, and Fig. 8 a plan, showing the mechanism for releasing the starting-lever of the loom. Fig. 9 is a plan of part of the sectional toothed ring and the positively-rotated member of the starting-lever-releasing mechanism. Fig. 10 is a side elevation showing part of the starting-lever-releasing mechanism. Figs. 2 and 3 and 7 to 10, inclusive, are drawn to a larger scale than Fig. 1. Figs. 4 to 6, inclusive, are drawn to a larger scale than Figs. 2 and 3 and 7 to 10.

Like letters indicate like parts throughout the drawings.

According to this invention the shuttles A, (see Figs. 1 to 3,) which are supported and propelled by jacks B, are each provided with

what may be termed an "obstruction-detector" C, (see Figs. 4 and 5,) which may take the form of a metal blade extending from near the fore end of the base of the shuttle up to near the top of the shed, as shown more clearly in Fig. 4. This detector C is preferably attached to the projecting fore end of a bar C', which can slide freely into the body of the shuttle A, so that should the detector C meet an obstruction in the shed it can give way or stop, while the shuttle continues to advance.

In order to make the bar C' slide as freely as possible, it is provided with a slot C², (see Fig. 4,) extending along its length, and is mounted on two rollers C³, mounted on the base or body of the shuttle A, as shown. The sliding bar C' is also provided with or connected to a catch C⁴, (shown more clearly in Figs. 3 and 4,) which normally projects through and engages with the side of an opening D' in a plate D. This plate D is preferably hinged at D² to the base or body of the shuttle A, and the catch C⁴ holds the free end D³ of this plate down against the action of a spring-actuated pin C⁵, (see Fig. 6,) acting on its under side, which pin C⁵ raises the free end D³ of the plate D immediately it is released. The upper end of the detector C may also work in a slit A', (see Figs. 5 and 6,) formed in the shuttle-plate A², which is connected to the body of the shuttle by members A³.

When the detector C meets with an obstruction in the shed and is consequently stopped while the shuttle A continues to advance, the catch C⁴ is, owing to its disposition, immediately disengaged from the hinged plate D, which latter is thus released, and its free end D³ is then raised by the spring-actuated pin C⁵. This rising movement of the plate D when released by a movement of the detector C relatively to the shuttle is utilized to stop the loom through the intermediary of mechanism hereinafter described. The rising movement of the plate D in any one of the shuttles employed is communicated to the mechanism for releasing the starting-lever by the following means.

Arranged round the exterior of the shuttle-race (see Figs. 1, 2, and 3) is what may be termed an annular "finger-ring" E, which is comprised of a number of segments having their ends journaled in bearings E', secured to the fixed framing E², so that each segment can be oscillated freely and independently of any of the other segments. This finger-ring

is provided with a number of fingers E^2 , which extend inward, so that their free ends occupy a position which is directly over that of the free ends D^3 of the hinged plate D in each shuttle A . The fingers E^2 are placed all round the shuttle-race a less space apart than that taken up by the free end D^3 of the plate D , so that when one of the latter is released and raised, as previously described, it will always engage one of the said fingers E^2 and oscillate the corresponding segment of the finger-ring E .

The whole of the segments comprising the finger-ring E are connected to the mechanism for releasing the starting-lever, which is preferably arranged as follows: Mounted loosely on the central column P of the loom is a wheel F , (see Figs. 1 and 7 to 10,) which is connected to the driving mechanism so that it is constantly rotated together with the operating cam-rings of the loom. This wheel F constitutes the positively-rotated member and is provided with a number of vertical bolts F' , (see Figs. 7 to 9 and 10,) which are carried at convenient intervals in corresponding openings in the rim of the said wheel F . Each of these bolts F' is held in its upper or normal position in which they are shown in Figs. 7 to 9 and 10 by a latch F^2 , (shown more clearly in Fig. 9,) and these latches F^2 are pivoted on the upper face of the rim of the wheel F , so that they can move angularly in the plane of rotation of the latter. Each latch F^2 is normally held in a notch in the corresponding bolt F' by a spring F^3 , connected to the latch and wheel F , respectively. Below the wheel F described in a second wheel G , which is rigidly mounted on the column P and serves to carry certain stationary parts of the apparatus. Between the wheels F and G is a wheel H , which is loosely mounted on the column P . The upper face of the rim of this wheel H is provided with ratchet-teeth H' , which are situated directly below the bolts F' in the running member or wheel F , so that when a bolt F' is released it falls and its lower end engages with the teeth H' in the wheel H , which latter is then connected to the running wheel F and is moved round with it. The lower ends of the bolts F' are cut, as shown, so as to engage the teeth H' on the wheel H , and in order to insure the bolts F' falling as described they may each be depressed by a spring F^4 acting on their upper ends.

The wheel H may be supported on antifriction-rollers H^2 , mounted on the fixed wheel G , as shown, so that it can move freely.

Above the wheel F is a toothed ring J , which is comprised of a number of independent segments equal in number to that of the finger-ring E , previously described. Each segment of the ring J , which is provided with ratchet-teeth J^6 (see Fig. 10) on its lower

edge, is carried by a pair of arms J' , which latter are each pivoted to a bracket J^2 , carried by a vertical support J^3 , attached to the fixed wheel G . The free inner ends of each pair of arms J' are connected together by a strap J^4 , and the latter are each provided with a lug J^8 , which is connected by a hinged or pivoted joint to the lower end of a connecting-link J^5 , (see Fig. 1,) the upper end of which is connected by a corresponding joint to an arm E^5 on the corresponding segment of the finger-ring E immediately above it, so that the oscillation of one of the latter, as previously described, depresses the corresponding segment of the toothed ring J .

When one of the segments of the toothed ring J is moved downward, the teeth J^6 , which are formed on its lower edge and more clearly shown in Fig. 10, engage with the free ends of one or more of the latches F^2 on the rotating member F and hold said latches. This action moves the latches F^2 clear of the corresponding bolt or bolts F' , which then fall and engage the teeth H' of the wheel H and lock the two together as previously described.

The segments of the ring J may be returned to their upper or normal positions again by springs J^7 acting on the arms J' . The latter are each carried through an opening in the corresponding vertical supports J^3 , which limits the extent of their movement.

A movement of the toothed wheel H releases the starting-lever of the loom and immediately stops the loom, preferably as follows: The starting-lever K , (see Fig. 1,) which controls, say, for example, a friction-clutch L , as shown, is held in the "on" position by a catch-link K' , which is pivoted to said lever and is provided with a catch K^2 to engage with a stop K^3 , attached to the fixed framing R . When the catch K^2 is released from the stop K^3 , the lever K is moved into the "off" position, in which it is shown by a spring K^4 or weight. The lower end of the lever K , to which the spring K^4 is connected, is shown out of its proper relation to the upper part. The periphery of the wheel H previously described is provided with a cam-recess H^3 , (see Figs. 7 and 8,) in which a projection M' on a lever M normally rests. The lower end of this lever M is pivoted to a bracket M^2 , secured to the fixed framing R , while its free upper end is connected to a link M^3 , (see Fig. 1,) provided with a cam-surface M^4 , which operates on the lower end of a bolt N , situated at the side of the stop K^3 for the catch-link K' . Any movement of the wheel H thus moves the upper end of the lever M outward, so that the cam part M^4 on the link M^3 raises the bolt N , and the latter moves the catch-link K' clear of the stop K^3 , thus releasing the starting-lever, which is returned to its normal position again by the

spring K⁴ and the loom stopped. When the toothed wheel H is again released by raising the fallen bolt F', it is returned to its normal position again by a spring H⁸, (see Fig. 8,) while the bolt F' is again retained by the spring-actuated latch F² in connection with it. The upper ends of the bolts F' are each provided with a loop F⁶, so that they can be raised by inserting a bar, or they may be all connected by any convenient means to a common lever or device for raising them, so that by operating said lever or device any bolt or bolts which have fallen may be conveniently raised.

15 It will be noted that the segments of the ring J, which are connected to the corresponding segments of the finger-ring E, also the wheel H, are provided with fine teeth, so that there is no time lost, owing to lost motion, in releasing a bolt F' and setting up a connection between the running member F and ring H when one of the segments of the ring J is depressed. The loom is thus stopped in the shortest period of time possible.

20 25 What I claim as my invention, and desire to secure by Letters Patent, is—

1. In a circular loom, the combination of a shuttle, means for propelling the same, a yielding obstruction-detector projection in front 30 of and carried by the shuttle, loom - stop mechanism and means for connecting the said detector and loom-stop mechanism; substantially as described.

2. In a circular loom, the combination of a shuttle, means for propelling the same, an obstruction - detector in connection with the shuttle, a spring-actuated plate in the shuttle which is normally held by the detector but is released when an obstruction is met, loom- 40 stop mechanism, and means for setting up a connection between said plate and loom-stop mechanism, substantially as described.

3. In a circular loom, the combination of a shuttle, means for propelling the same, an obstruction - detector in connection with the shuttle, a spring-actuated plate in the shuttle which is normally held by the detector but is released when an obstruction is met, a series 45 of fingers arranged round the shuttle-race for the plate to engage with, loom-stop mechanism, and means for carrying and connecting said fingers to the loom-stop mechanism, substantially as described.

4. In a circular loom, the combination of a shuttle, means for propelling the same, obstruction-detector mechanism in connection with the shuttle, a series of fingers arranged round the shuttle-race to set up a connection with the detector mechanism of the shuttle, 55 loom-stop mechanism, and a connection between the latter and the said fingers, substantially as described.

5. In a circular loom, the combination of a shuttle, means for propelling the same, ob-

struction-detector mechanism in connection 65 with the shuttle, a series of fingers arranged round the shuttle-race to set up a connection with the detector mechanism of the shuttle, a segmental finger-ring, loom-stop mechanism, and connections between the latter and 70 the segments of the finger-ring substantially as described.

6. In a circular loom, the combination of a shuttle, means for propelling the same, obstruction-detector mechanism comprised of a 75 sliding bar carrying a blade in front of the shuttle, a spring-actuated plate in the shuttle, a catch on the sliding bar to hold said plate, a series of fingers arranged round the shuttle-race to set up a connection with said plate, a segmental ring to carry the fingers, loom- 80 stop mechanism, and connections between the latter and the segments of the finger-ring, substantially as described.

7. In a circular loom, the combination of a shuttle, means for propelling the same, obstruction-detector mechanism in connection with the shuttle, a series of fingers arranged round the shuttle-race to set up a connection with the detector mechanism in the shuttle, a 85 segmental ring to carry the fingers, a running member, bolts in said member, retaining-latches for said bolts, a segmental toothed ring to engage said latches, a connection between the toothed segments and the segments 90 of the finger-ring, a toothed member which is engaged by a fallen bolt, and means for releasing the starting-lever operated by the latter, substantially as described.

8. In a circular loom, the combination of a shuttle, means for propelling the same, obstruction-detector mechanism in connection with the shuttle, a series of fingers arranged round the shuttle-race to set up a connection with the detector mechanism in the shuttle, a 100 segmental ring to carry the fingers, a running member, bolts in said member, retaining-latches for said bolts, a segmental toothed ring to engage said latches, a connection between the toothed segments and the segments 105 of the finger-ring, a toothed member which is engaged by a fallen bolt provided with a cam part, a cam-lever operated by said cam part, a starting-lever catch, and a connection between the cam-lever and starting-lever catch, 110 substantially as described.

9. In a circular loom, the combination of a shuttle, means for propelling the same, an obstruction-detector in the shuttle, a spring-actuated plate which is normally held by the detector, a series of fingers arranged round the shuttle-race to set up a connection with the plate in the shuttle, a segmental ring to carry the fingers, a positively-rotated member, bolts in said member, retaining - latches for said bolts, a segmental toothed ring to engage said latches, a connection between the toothed segments and the segments of the finger - ring, a 120

toothed member which is engaged by a fallen bolt provided with a cam part, a cam-lever operated by said cam part, a starting-lever catch, and a connection between the cam-lever and starting-lever catch, substantially as described.

In testimony whereof I have signed my

name to this specification in the presence of two subscribing witnesses.

CHARLES GREY HILL.
